HANDLE FOR PORTABLE ARTICLES

Henry Allen Avery, Groton, N. Y., assignor to L. C. Smith & Corona Typewriters, Inc., Syracuse, N. Y., a corporation of New York

Application January 6, 1939, Serial No. 249,562

3 Claims. (Cl. 190—57)

The invention relates to improvements in carrying handles for portable articles or bodies, and has for its principal objects to provide an efficient and sturdy handle device, and to provide a handle device offering little protrusion when not in use and including a hand grip element which may be flattened for compactness or arched for use and will remain either flattened or arched until it is desired that its condition be changed.

Other objects and advantages of the invention will appear from the following detailed description.

In the accompanying drawing, wherein a preferred form of handle device embodying the invention is shown applied to a wall of a carrying case for a portable typewriter,

Fig. 1 is a plan view showing the hand grip element of the handle device collapsed or flattened against the case wall;

Fig. 2 is a sectional view on the line 2—2 of Fig. 1;

Fig. 3 is a view similar to Fig. 2 but showing the grip element of the handle device drawn out into, and held in, position for use;

Fig. 4 is a sectional view on the line 4—4 of Fig. 2;

Fig. 5 is a perspective view of the hand grip element, a part of which at one end is broken away;

Fig. 6 is an enlarged sectional view on the line 6—6 of Fig. 1; and

Fig. 7 is a perspective view of one of the pair of combined anchoring and guiding elements for the hand grip element of the handle device.

In the drawing, 10 designates a portion of a flat and rigid metal wall of a portable article or body to be carried as, for example, a wall of a carrying case for a portable typewriter, to which wall is permanently connected a handle device by which may be carried the article or body of which the wall is a part. This handle device comprises generally a resilient hand grip element 11 and a pair of combined anchoring and guiding elements 12 for the ends of the hand grip element, the said pair of elements 12 being permanently attached to the wall 10 of the article to be carried.

The hand grip element 11 is of such construction that it is resiliently flexible longitudinally from a normally straight state, but is non-extensible longitudinally. As shown, the grip element 11 comprises a strap or bar 13 of spring steel enclosed in a suitable tubular flexible covering. The covering shown comprises two leather straps or strips 14 stitched together adjacent their longitudinal edges by lines of stitching 15

to form a flat tube in which the strap or strip 13 of spring metal is housed. The spring metal strap 13 is provided adjacent each end thereof with a closed slot 16 elongated in the direction of the length of the strap. Each leather strap is formed at each end thereof with a longitudinal slot 17 which extends inward from the adjacent end of the leather strap to the inner end of the adjacent slot 16 in the metal strap. Slots 16 and 17 are of equal width and are located midway the longitudinal edges of the hand grip element so that the slot 16 adjacent each end of the hand grip element registers in plan with the inner portions of the two adjacent slots 17, as shown. The slots 16 and 17 render the end portions of the handle more flexible and more readily bendable than the unslotted body of the handle.

The hand grip element 11 normally tends to flatten or straighten out into the flat strap form or condition shown in Figs. 1, 2, 4 and 5, but may be bowed or flexed resiliently longitudinally. Each of the combined anchoring and guiding elements 12 comprises a rigid sheet metal housing and, in the construction shown, is permanently attached to wall 10.

Each element or housing 12 has a flat rectangular top wall 18 from which depends three walls of equal height, namely, two side walls 19 and an end wall 20 connecting said side walls, the fourth side of the housing being open. Walls 19 and 20 of each housing are provided with integral pendant lugs 21 passed down through slots or apertures in wall 10 and bent outward or clinched against the under face of the wall 10 to rigidly hold the housing in place at the outer face of wall 10. The two elements or housings are fastened to wall 10 with their open ends facing each other and with their end walls 20 spaced apart a distance at least equal to, and preferably slightly exceeding (as shown), the length of the element 11 in the straightened condition of the latter. Side walls 19 of each housing are spaced apart a distance at least equal to, and preferably slightly greater than, the width of element 11 to permit free sliding of the ends of element 11 in the housings 12. The height of the side walls and end wall of the housings also equals, or is preferably slightly greater than, the thickness of element 11 to permit free sliding of the ends of element 11 in the housings 12.

The two housings or elements 12 are provided with means 22 for permanently retaining in said housings, for positively limited sliding movement in the housings, the end portions of the hand grip element 11, which means are so related

to the element 11, wall 10 of the case or other object to be carried, and the top walls 18 of the two housings, that upon grasping of the straightened element 11 between the housings and pulling it upward from wall 10 said element will be flexed or bowed upward from wall 10 intermediate the housings throughout the major portion of the length of element 11 and the end portions of element 11 will be flexed or bowed reversely to the main intermediate bowed portion of said element to automatically frictionally bind the under face of element 11 at each end thereof on wall 10 within the respective housings under spring pressure and to automatically frictionally bind the upper face of element 11 under spring pressure against the inner edges of the top walls 18 of the two housings 12. The means 22 provided on each housing 12 comprises, in the construction shown, an angular extension 22 of the top wall 18 of each housing extending through the adjacent slot 16 for limited relative movement between the extension and the adjacent end portion of the element 11 longitudinally of slot 16.

The extension 22 of each housing wall 18 extends horizontally inward from the medial portion of wall 18 of the housing a substantial distance toward the other housing and then extends vertically downward to wall 10, being provided at the lower end of its vertical portion with a lug 23 which passes through a suitable aperture or slot in wall 10 and is bent or clinched against the under face of wall 10. The distance between the vertical portions of extensions 22 of the housings equals, or slightly exceeds (as shown), the distance between the inner ends of slots 16 of the straightened element 11, and the distance between said vertical portion of extension 22 and the end wall 20 of each housing equals or slightly exceeds the distance between the inner end of slot 16 and the adjacent end of element 11, to thereby permit said element 11 to fully straighten and assume a flattened condition against wall 10 with said vertical portions of extensions 22 of elements 12 located at the inner ends of the two sets of slots in element 11, as shown in Figs. 2 and 4. The distance between the outer end of each slot 16 and the adjacent end of element 11 exceeds the depth of housings 12.

It will be apparent, therefore, that, upon grasping of the flattened hand grip element and pulling of the latter outward (as shown in Fig. 3), the main medial portion of the hand grip element 11 will be resiliently flexed or bowed or arched upward from the wall 10, the housed end portions of element 11 will slide inward toward each other until positively arrested by extensions 22, and there will be caused a reverse bending of the more readily bendable end portions of element 11 with respect to the curvature of the main hand-gripped and upwardly arched medial portion of element 11 which will cause the upper face of element 11 to frictionally bind on the inner edges of the top walls of elements 12 and will cause the lower face of element 11 to frictionally bind on the upper face of wall 10 at each end of element 11. The result of the resilient cramping effect or frictional bind at longitudinally offset points at opposite faces of the hand grip element 11 thus attained at each end portion of element 11 is that said element will automatically be frictionally locked in its arched position of use shown in Fig. 3 and will there remain until a downward force toward wall 10 is exerted on the upwardly arched main or medial portion of ele-

ment 11. It will also be observed that the described construction affords, with a given spacing of elements 12, a maximum arc of handle element 11 available for grasping by the hand.

5 The abutments 22 permit limited sliding of the ends of the hand-grip element 11 relatively to the anchoring and guiding housings sufficient to permit compact flattening of element 11 against wall 10 when not in use, and to permit arching or 10 bowing of said element 11 into a frictionally retained position of use. Preferably the inner edge of wall 18 of each housing 12 is bent or rolled upward at each side of extension 22 as shown at 15 24 to avoid cutting and scraping action on the upper face of the handle element 11.

What I claim is:

1. The combination with a manually carriable article, of an elongated and inherently self-straightening carrying handle for said article 20 comprising a flat thin steel spring strip enclosed in a flexible cover and resiliently bendable to arch the handle relatively to the article for use and having therein a pair of longitudinally extending and aligned closed slots through the steel 25 strip each spaced a substantial distance from a different end of the handle the ends of the cover for said strip being slotted at its ends in register with the slots in the steel strip the end portions of the handle from the inner ends of the slots to the ends of the handle having greater flexibility than the non-slotted body of the handle between said inner ends of said slots, and a spaced pair of handle anchor boxes fixedly held to the article 30 and each having an open end facing toward the other box for sliding engagement of the handle in said boxes to permit straightening of the handle and arching of the handle between said boxes for use, said handle boxes being so spaced longitudinally of the handle and of such length that each handle slot extends for a substantial part of its length within the adjacent anchor box when the handle is straightened, and each handle box having a narrow angular arm of less width than the adjacent handle slot and extending 35 from the top of the anchor box a substantial distance toward the other anchor box and thence through the adjacent handle slot toward the article and anchored to the article to form stops spaced outward from the forward edges of the anchor boxes, the said arms entering the slots when the handle is arched to cause the upper surface of the handle to contact the forward edges of the anchor boxes inward from said stops and bind the more flexible ends of the handle on the surface of the article to which the handle is attached.

2. The combination with a manually carriable article, of an elongated and inherently self-straightening carrying handle for said article 60 comprising a flat thin steel spring strip enclosed in a flexible cover and resiliently bendable to arch the handle relatively to the article for use and having therein a pair of longitudinally extending and aligned closed slots through the steel strip each spaced a substantial distance from a different end of the handle the ends of the cover for said strip being slotted at its ends in register with the slots in the steel strip and extending to the ends of the handle to provide at each end of the handle a long bendable handle end portion having greater flexibility than the non-slotted body of the handle between said slots, and a spaced pair of handle anchor boxes 65 fixedly held to the article and each having an

open end facing toward the other box for sliding engagement of the handle in said boxes to permit straightening of the handle and arching of the handle between said boxes for use, said handle boxes being so spaced longitudinally of the handle and of such length that each handle slot extends for a substantial part of its length within the adjacent anchor box when the handle is straightened, and each handle box having a narrow angular arm of less width than the adjacent handle slot and extending from the top of the anchor box a substantial distance toward the other anchor box and thence through the adjacent handle slot toward the article and anchored to the article to form strips spaced outward from the forward edges of the anchor boxes, the said arms entering the slots when the handle is arched to cause the upper surface of the handle to contact the forward edges of the anchor boxes inward from said stops and bind the more flexible ends of the handle on the surface of the article to which the handle is attached.

3. The combination with a manually carriable article, of an elongated and inherently self-straightening carrying handle for said article comprising a flat thin steel spring strip enclosed in a flexible cover and resiliently bendable to arch the handle relatively to the article for use and having therein a pair of longitudinally ex-

10 tending and aligned closed slots through the steel strip each spaced a substantial distance from a different end of the handle the ends of the cover for said strip being slotted at its ends in register with the slots in the steel strip, and a spaced pair of handle anchor boxes fixedly held to the article and each having an open end facing toward the other box for sliding engagement of the handle in said boxes to permit straightening of the handle and arching of the handle between said boxes for use, said handle boxes being so spaced longitudinally of the handle and of such length that each handle slot extends for a substantial part of its length within the adjacent anchor box when the handle is straightened, and each handle box having a narrow angular arm of less width than the adjacent handle slot and extending from the top of the anchor box a substantial distance toward the other anchor box and thence through the adjacent handle slot toward the article and anchored to the article to form stops spaced outward from the forward edges of the anchor boxes, the said arms entering the slots when the handle is arched to cause the upper surface of the handle to contact the forward edges of the anchor boxes inward from said stops and bind the flexible ends of the handle on the surface of the article to which the handle is attached.
